US0D1092597S

(12) **United States Design Patent** (10) **Patent No.:** **US D1,092,597 S**
(45) **Date of Patent:** **** Sep. 9, 2025**

(54) **CAMERA**

(71) Applicant: **GENETEC INC.**, St-Laurent (CA)

(72) Inventor: **Nathaniel Lalande-Bertrand**,
Saint-Eustache (CA)

(**) Term: **15 Years**

(21) Appl. No.: **29/978,826**

(22) Filed: **Dec. 16, 2024**

Related U.S. Application Data

(63) Continuation of application No. 29/927,972, filed on Feb. 7, 2024, now Pat. No. Des. 1,060,469, which is a continuation of application No. 29/865,621, filed on Aug. 4, 2022, now Pat. No. Des. 1,042,592.

(57) **CLAIM**

The ornamental design for a camera, as shown and described.

DESCRIPTION

FIG. 1 is a front and right side perspective view of a camera showing my new design;

FIG. 2 is a back and left side perspective view thereof;

FIG. 3 is a front view thereof;

FIG. 4 is a back view thereof;

FIG. 5 is a right-side view thereof;

FIG. 6 is a left-side view thereof;

FIG. 7 is a top view thereof; and,

FIG. 8 is a bottom view thereof.

The broken lines depict portions of the camera that form no part of the claimed design.

The dash-dot-dash broken lines denote the boundary of the claim and form no part of the claimed design.

1 Claim, 8 Drawing Sheets
